United States Patent Office.

GEORGE E. EVANS, OF BOSTON, MASSACHUSETTS

Letters Patent No. 69,328, dated October 1, 1867.

IMPROVED CENTRIFUGAL APPARATUS FOR WASHING SUGAR.

The Schedule referred to in these Letters Patent and making part of the same.

TO ALL WHOM IT MAY CONCERN:

Be it known that I, GEORGE E. EVANS, of Boston, in the county of Suffolk, and State of Massachusetts, have invented an improvement in Centrifugal Apparatus for Washing Sugar; and I do hereby declare that the following is a full and exact description thereof, reference being had to the accompanying drawings, and to the letters of reference marked thereon.

The object of my invention is to increase the efficiency of what is commonly known as the centrifugal sugar machine, and it consists in the employment of a new means of attaching and detaching the circular partition or basket invented and patented by Alexander Mackey and Eberhardt Müller, their patent being dated March 27, 1866, which circular partition is described by them as "placed within and concentric with the revolving cylinder of the machine, and composed like it of wire cloth, or other foraminated material, by which means the sugar is kept near the periphery of said cylinder in such a way as to insure the full benefit of the centrifugal force generated by the rapid rotation thereof." The invention of said Mackey and Müller is described by them also to consist in the employment of a novel means of retaining the said partition in its place. I do not claim the use of said partition, my invention being limited to an improvement of so much of the invention of Mackey and Müller as consists in the use of the partition above referred to, by providing a new means of keeping it in place, and dispensing with cumbersome and heavy apparatus used by them for this purpose.

In the machinery used by Mackey and Müller a circular platform, indicated in the drawing attached to their specification as "the circular platform S," is used to keep the partition in place. In practice this platform is frequently dispensed with by them, and cleats or segments of the platform are used to keep the partition in place. Both the platform and the cleats are of great inconvenience, as causing obstructions in shovelling out the sugar from the centrifugal tub after the sugar has been washed. The said Mackey and Müller also make use of a lid, which is thus described: "The lid R is hinged at one side, and it is annular in form; it covers the annular chamber E, and its inner edge pressing down upon the top of the partition prevents the said partition from being displaced from its hold upon the platform S." The disadvantages of connecting the lid with the partition, as is done in Mackey and Müller's machine, is the great weight of lid, some eighty pounds, the resistance which it makes in the revolution of the machine requiring nearly double the power required in machines with my improvement, and the inequality in the movement of the machine caused by the weight being on one side. In my improvement I dispense with the platform E and the lid R of Mackey and Müller's machine.

The construction of my machine is shown in the accompanying drawings, making a part of my specification.

A is a centrifugal tub, provided with wire-gauze sides; B is a movable circular partition or basket provided with a bottom or frame, shown in the plan, Figures III and IV. The sides of this partition or basket may be made of wire gauze, as shown in Figure II, or they may be made of sheet metal without foramination, a peculiar feature of my invention, as shown in Figure I. This partition or basket is kept in place by means of a hollow cone of sheet metal, D, which fits over the inner cone E, which supports the spindle on which the centrifugal revolves. In case the inner cone is dispensed with a simple shaft may be placed in the bottom of the centrifugal tub, in which case a socket to fit over this central shaft is substituted for the hollow cone D. A device for lifting the basket B is shown at F, Figure II. This consists of two bent pieces of metal fastened together in such a manner as to form a cross, the ends of the arms fitting under the rim of the basket, when it is desired to lift the basket, the cross-pieces being attached at their point of intersection to a cord passing over a pulley.

When the machine is to be charged with sugar the movable cover for distribution, G, Fig. I, is placed over the basket B, which prevents the admission of sugar within the basket B, but allows the sugar to fill the space between the sides of the centrifugal tub A and the partition. The sugar is dropped from the charger, making a wall between the basket B and the sides of the centrifugal tub A. The machine is then revolved. As soon as the revolution commences I lift the basket, and the centrifugal force keeps the wall in place. When the basket is made of wire gauze it is not necessary to lift it out of the tub, but I prefer to dispense with the wire gauze and to have the sides of the basket of sheet metal. When the basket is lifted out of the centrifugal tub the water can be played directly upon the wall of sugar, the washing being more perfect when there is no obstruction from the wire gauze.

I do not claim the use of a circular inner foraminated partition or cylinder in centrifugals as my invention, but limit my claims to the improved partition or cylinder, as described, and to the mode of operating the same. What I claim as my invention, and desire to secure by Letters Patent, is—

1. The movable inner circular cylinder or partition B in centrifugal sugar machines, either with or without foraminations, the same being capable of being attached without alteration of the centrifugal tub, by means of a conical or cylindrical socket fitting upon a central conical or cylindrical shaft, substantially as described.
2. Constructing the inner cylindrical partition B, in centrifugal sugar machines, of sheet metal or any equivalent material, without foraminations or interstices, substantially as described.
3. Operating the inner cylindrical partition B, when made without foraminations, to make a wall of sugar by lifting the same after the rotation of the centrifugal has commenced.

GEO. E. EVANS.
